UNITED STATES PATENT OFFICE

162,935

SODA FOUNTAIN

William S. Connell, Norwood Park, Ill.

Application August 10, 1949, Serial No. 4,405

Term of patent 14 years

(Cl. D2—3)

To all whom it may concern:

Be it known that I, William S. Connell, a citizen of the United States, residing at 5001 Olcott Street, Norwood Park, in the county of Cook and State of Illinois, have invented a new, original, and ornamental Design for a Soda Fountain, of which the following is a specification, reference being had to the accompanying drawings, forming a part thereof:

Fig. 1 is a front perspective view of a soda fountain embodying my new design;

Fig. 2 is a perspective view taken from a point slightly above and to one side thereof, and

Fig. 3 is a perspective view taken from a point slightly above and to the opposite side thereof.

I claim:

The ornamental design for a soda fountain, as shown.

WILLIAM S. CONNELL.
